UNITED STATES PATENT OFFICE.

THEODORE N. HANSEN, OF SEATTLE, WASHINGTON.

POCKET FOLDING STOOL.

Application filed December 15, 1926. Serial No. 154,933.

My invention relates to pocket folding stools and certain objects of the invention are to provide a stool of very durable and substantial construction that may be folded 5 in such compact form as to be carried in the pocket. Another object is to provide a folding stool whose top or seat may also serve as the bottom of the casing in which it is carried in the folded position. Further objects are to provide novel folding joints and 10 braces together with means for strengthening same when in the set-up position.

With the above and other objects in view which will appear as the description proceeds, the invention consists of the novel construction, adaptation, combination and arrangement hereinafter described and claimed. These objects are accomplished by 15 devices illustrated in the accompanying drawings, wherein:—

Figure 1 is a view in perspective of the stool in the set-up position;

Fig. 2 is a view in transverse vertical section of same;

Fig. 3 is a view in longitudinal vertical section;

Fig. 4 is an enlarged view in side elevation of the stool in a completely folded position within the casing which is shown in 30 section; and

Fig. 5 is a top plan view of same in the folded position with the casing removed.

Referring to the drawings throughout which like reference numerals designate like 35 parts, the numeral 5 indicates the seat of the stool that is preferably made of relatively thin metal and in rectangular oblong shape. Depending lugs 6, 7, 8 and 9 are secured to said seat in any suitable manner. Referring to Figs. 1 and 5 it will be noted that the lugs 6 and 7 are spaced a little further apart than are the lugs 8 and 9. Each of said lugs is provided with a slot 10 that is in 40 the shape of an inverted keyhole having an enlarged round portion and a reduced rectangular portion for reasons presently apparent.

The four legs of the stool each comprise upper sections 11, middle sections 12, and 45 lower sections 13, all of which are preferably made of metal and square in cross section. The upper end portions of each of the upper sections are provided with a short stud bolt 14 fixedly secured thereto and provided with short square shanks and large heads. Said square shanks may be pushed

upwardly into the rectangular portions of the slots 10 and held there by hooks 15 pivotally secured to the lugs to hold the legs securely in place when the stool is in the 60 set-up position as will be readily understood.

The leg sections 11 are each connected to the sections 12 by short links 16 pivoted at each end to said sections, and likewise the 65 sections 12 are connected to the sections 13 by short links 17 pivoted at each end to said sections. Said links fit in slots provided in the ends of said sections and are flush therewith when the legs are in the set-up position. Sleeves 18 resting on pins 19 are adapted to fit said sections snugly and are arranged to slidably enclose the joints formed by the links 16, while similar sleeves 20 resting on pins 21 enclose the joints of 75 the links 17.

In order to hold the four legs of the stool in proper slantwise spaced relation in the set-up position I have provided four novel braces in the form of the letter K. Said 80 braces each comprise members 22, 23, 24 and 25 having their inner ends pivotally connected at 26. Each of the members 22 is pivoted to the lower leg sections 13 at 27 and the outer ends of the other three members are each provided with a slot 28 adapted to engage a pin 29 in said sections to hold the legs in rigid position as clearly shown in Fig. 1 of the drawings.

Assuming that the stool is in the set-up 90 position as shown in Fig. 1, in order to fold same it is turned bottom upwards with the seat 5 resting on the floor. The sleeves 18 will drop by gravity against the lugs 6, 7, 8 and 9, while the sleeves 20 will slidably rest 95 against the pins 19 thus freeing the joints at 16 and 17. Each of the four K-braces is then pivotally folded together against their respective members 22 which is then folded against the leg sections 13 as indicated in 100 Figs. 2 and 3. The hooks 15 are then disengaged and the square shanks of the bolts 14 are slipped into the round portions of the slots 10 so that they may turn freely.

It will now be obvious that the three 105 sections of the four legs may be folded together in zig-zag fashion and rest on the bottom of the seat 5. As hereinbefore mentioned the lug 6 is disposed in offset relation with the lug 8 so that the sections and braces 110 that are collectively pivoted to the former lug may rest alongside those pivoted to the

latter lug thereby taking up less space. The same, of course, may be said of the other two legs that are pivoted to the lugs 7 and 9. The disposition of the legs in the folded position is substantially as shown in Fig. 5 although the device is not limited to the exact positions shown.

For the purpose of carrying the stool in the pocket I have provided a case 30 having a hinged door 31 at one end and provided with a flange 32 around its bottom. The seat 5 of the stool may be slipped into said casing with said flange engaging its edges and said door closed with a spring 15 clasp 33 snapped into a slot 34 in said seat. I usually provide a longitudinal partition 35 for said casing, a portion of which is shown in Fig. 4 and its position indicated by dotted lines in Fig. 5. Said partition divides the 20 casing into two equal compartments and prevents the leg sections from interfering with each other as will be readily understood.

Having thus described my invention what I claim and desire to secure by Letters Patent of the United States is:—

25 A pocket folding stool comprising a seat, four depending lugs for the seat having inverted keyhole slots, four legs each comprising

30 three foldable sections pivotally connected, slidable sleeves adapted to hold said sections in rigid set-up position, the uppermost of said sections having square bolts 35 adapted to fit snugly within the upper rectangular portions of said keyhole slots in the set-up position, means for locking said bolts in said rectangular slot portions, said bolts adapted to be shifted to pivotal disposition within the lower round portions of said slots, four K-braces each comprising 40 four pivotally connected members, the end of one member of each of said K-braces pivotally secured to the lowermost of each of said leg sections, means for fastening the ends of the other three brace members to the two adjoining lowermost leg sections in the 45 set-up position, each of said K-braces adapted to be folded in compact alignment against its associated leg section, a casing for the stool in its folded position, and the 50 seat arranged to serve as the bottom of the casing in the folded position.

In witness whereof, I hereunto subscribe my name this 9th day of December A. D. 1926.

THEODORE N. HANSEN.
